MULTIPLE UTILITY RACKS

Edward N. Brown, Alhambra, Calif.

Application July 15, 1957, Serial No. 671,899

11 Claims. (Cl. 211—26)

This invention relates to utility racks in general and, in particular, to a multiple utility rack that is economically made of wire and is adapted for extended use by adding additional trays.

As is well known in the prior art, particularly with relation to floral displays, racks made from wire forms are common. Such racks, however, are usually of unitary construction and are not adapted to various modifications and additions.

It is an object of my invention, therefore, to supply a basic unit rack which is adapted to hold various objects, particularly electric lamp bulbs.

Another object of my invention is to provide a basic unit rack which is adapted to receive and support one or more additional utility trays.

A further object of my invention is to provide a basic unit rack which is adapted to support one or more utility trays which may be added or removed as desired.

A still further object of my invention is to provide a basic unit rack with one or more utility trays suspended therefrom, all such racks and trays being constructed of wire forms which may be formed and assembled with ease and economy.

Other objects and advantages of my invention will appear in connection with the following specification and drawing wherein like reference characters denote like parts throughout the several views and wherein:

Figure 1 is a perspective view of my invention comprising a basic unit rack and two additional utility trays.

Fig. 2 is an end elevation of one of the utility trays. With reference to the figures, basic unit rack 10 is formed of a rectangle of wire 11 to which is attached, by spot welding or other suitable fastening means, a multiplicity of open-ended, generally hairpin-shaped, wire forms 12. These wire forms 12 have a loop or connecting portion 14 and two converging legs 16. All of the loop portions 14 are fastened by brazing, soldering, or other suitable means to one side of the rectangle 11 while the ends of the legs 16 are similarly secured to the opposite side of the rectangle 11. A curvilinear longitudinal wire 18 is provided to form a brace for the wire forms 12 and is so curved with relation to the loop portions 14 and the legs 16 as to form properly shaped receptacles for the support of the electric lamp bulbs placed therein. This longitudinal wire 18 may be secured to the ends 20 of the rectangle 11 and to the wire forms 12 by spot welding or brazing.

It should be noted that the longitudinal wire 18 and the wire forms 12 form two types of lamp bulb supports. That shown as supporting lamp bulb 22 (shown in phantom) comprises an outwardly extending curve 24 of the longitudinal wire 18, i.e., curve 24 extends in the same direction as the loop portions 14, and the adjacent sides 16 of two of the wire forms 12. These two adjacent sides converge rearwardly which convergence tends to force the lamp bulb 22 forwardly into the bight of the curve 24 away from the rear side 26 of the rectangle 11. The support for lamp bulb 28 comprises the back-

2

wardly extending curve 30 of the longitudinal wire 18 and the forwardly extending loop portion 14 of the wire form 12.

Basic unit rack 10 is provided with two brackets 32 and 34 which are movably hooked or secured to each of the ends 20 of the wire rectangle 11. As shown, these brackets are made of a single piece of wire, generally in a triangular configuration, and have a loop 35 at the upwardly extending apex thereof which may be used to fasten the basic unit rack to the wall or other supporting structure. While not shown, it should be understood that these brackets 32 and 34 will fold inwardly so that the basic unit rack may be packaged in a flat container or in the top or bottom parts of a container of lamp bulbs. It should now be apparent that the configuration of the wire support holding lamp bulb 22 is so formed with its rearwardly converging sides that the lamp bulb will be held away from the wall or other structure supporting the basic unit rack 10.

Utility trays 40 and 42 are provided to be added to and supported from the basic unit rack 10 and from each other as may be desired.

These utility trays comprise a rectangle of wire 44 having dimpled or crimped ends 46. Downwardly extending or flat-bottomed U-shaped wires 48 are provided to shape the tray portion. These wires 48 may be spot-welded or brazed to the longer longitudinal sides of the rectangle 44. Longitudinal braces 50 are furnished to render proper support to the wires 48 to which they are fastened, to keep them properly separated and generally to strengthen the entire tray structure.

Each tray is provided with four supporting hooks 52, one at each corner of the rectangle 44. These hooks 52 are provided with an open curve or bend at its upper end for attachment to the rack or tray next above while the lower end is formed with a closed curve or bend which is secured around the end 46 of the rectangle 44. The dimpled or crimped ends 46 are formed with two dimples or crimps 54 which serve the dual purpose of keeping the hooks 52 in their proper places at the corner of the rectangle 44 as well as providing a hooking-on portion for the hooks 52 of the tray next below. If it were not for these dimples or crimps, the upper ends of the hooks 52 could slide together and the lower tray would be insecurely supported.

The ends 20 of the wire rectangle 11 used in the basic rack unit 10 may be provided with crimps 54, as shown, or these crimps may be omitted for convenience of manufacture when the basic rack unit is sold separately as part of a package of electric lamp bulbs.

It can be seen that my multiple utility rack is light in weight and may be assembled or disassembled with equal ease. The simple wire forms are few in number, necessitating a minimum number of jigs and fixtures for forming the two units. While I have shown the basic unit rack as being particularly adapted to provide a convenient and ready holder for spare lamp bulbs, it should be realized that other objects could be held with equal facility. The additional trays may be used for holding fuses, tools, or other household devices.

Having thus described my invention and shown one embodiment thereof, I do not intend to be unnecessarily limited thereby but only by the scope of the appended claims wherein I claim:

1. A foldable wire rack for storing and supporting electric lamp bulbs or the like comprising, in combination: a horizontal rectangle of wire having two relatively long inner and outer sides and two shorter ends; foldable means connected to the ends of said rectangle for securing said rack to a vertical supporting structure; a plurality of hairpin-like wire forms secured transversely of said rectangle, said wire forms comprising a pair of

converging legs connected at the converging end by a connecting portion, said connecting portion being secured to the outer side of said rectangle and the ends of said converging legs being secured to the inner side of said rectangle, and said wire forms being spaced from each other and the ends of said rectangle whereby a substantial space is left between the adjacent legs of the wire forms and between one wire form leg and the ends of said rectangle; and a curvilinear longitudinal wire secured to the ends of said rectangle and to the legs of the said wire forms, said curvilinear longitudinal wire being disposed substantially midway between the sides of said rectangle.

2. A foldable wire rack for storing electric light bulbs and the like as claimed in claim 1 wherein said curvilinear longitudinal wire has a series of curves alternately extending toward the outer and inner sides of said rectangle, the points of curvature of said curves being defined by the junctures of said curvilinear wire with the ends of said rectangle and the legs of said wire forms, said curves being coplanar with said rectangle.

3. A foldable wire rack for storing electric lamp bulbs and the like as claimed in claim 1 wherein said inwardly and outwardly extending curves are so disposed with relation to said wire forms that an inwardly extending curve is contained between the legs of a wire form whereby a lamp bulb supporting receptacle is formed between the outwardly extending connecting portion of said wire form, the legs of said wire form and the inwardly extending curve of said curvilinear longitudinal wire.

4. A foldable wire rack for storing electric lamp bulbs or the like as claimed in claim 1 wherein said inwardly and outwardly extending curves are so disposed with relation to said wire forms that an outwardly extending curve is contained between the adjacent legs of a pair of wire forms and between a leg of a wire form and the end of said rectangle adjacent thereto whereby a lamp bulb supporting receptacle is formed between the adjacent legs of said pair of wire forms, said outwardly extending curve of said curvilinear longitudinal wire and the inner side of said rectangle and a similar receptacle is also formed between the leg of a wire form, the end of the said rectangle adjacent thereto, said outwardly extending curve of said curvilinear wire and the inner side of said rectangle.

5. A foldable wire rack for storing electric lamp bulbs or the like as claimed in claim 4 wherein the said adjacent legs of said pair of wire forms converge inwardly toward said inner side of said rectangle whereby when said lamp bulb is placed in said receptacle formed between the adjacent legs of said pair of wire forms, said outwardly extending curve of said curvilinear longitudinal wire and a portion of the inner side of said rectangle, said lamp bulb is forced outwardly toward said curvilinear wire and away from said inner side of said rectangle and said supporting structure.

6. A foldable wire rack for storing electric lamp bulbs or the like comprising in combination: a horizontally disposed rectangle of wire having relatively long inner and outer sides and two shorter ends; foldable means movably connected to the ends of said rectangle for securing said rack to a vertical supporting structure, said inner side of said rectangle being disposed adjacent to said supporting structure; a plurality of hairpin-like wire forms secured transversely of said rectangle, said wire forms having a closed end and an open end with all of the closed ends secured to the outer side of said rectangle and all of the open ends secured to the inner side of said rectangle, said wire forms being spatially disposed with relation to each other and to the ends of said rectangle; a curvilinear longitudinal wire brace secured to the ends of said rectangle and to the said wire forms, said brace being disposed substantially midway between the sides of said rectangle; first receptacle means for holding said elec-

tric lamp bulbs, said first receptacle means comprising selected portions of said rectangle, said wire forms, and said curvilinear brace; and second receptacle means for holding said electric lamp bulbs, said second receptacle means comprising selected portions of said wire forms and said curvilinear brace, said first and second receptacle means being alternately disposed with relation to said curvilinear brace, said first receptacle means being disposed toward the inner side of said rectangle and said second receptacle means being disposed toward the outer side of said rectangle.

7. A foldable wire rack for storing electric lamp bulbs or the like as claimed in claim 6 further characterized by providing each of said ends of said rectangle with a pair of downwardly extending crimps, one of said crimps being disposed adjacent to each of the corners of said rectangle.

8. A multiple utility rack formed of wire for storing electric lamp bulbs or the like and other miscellaneous small household devices comprising, in combination: a foldable wire rack for storing electric lamp bulbs as claimed in claim 7; a horizontal utility tray suspended vertically underneath said foldable wire rack; and means for suspending said tray from said foldable wire rack.

9. A multiple utility rack formed of wire for storing electric lamp bulbs or the like and other miscellaneous small household devices comprising, in combination: a foldable wire rack for storing electric lamp bulbs as claimed in claim 7; a first horizontal utility tray suspended vertically underneath said foldable wire rack; suspension means for suspending said first tray from said foldable wire rack; a plurality of horizontal utility trays suspended vertically underneath said foldable wire rack and said first utility tray; and suspension means for said plurality of horizontal utility trays whereby each of said plurality of trays is suspended from the horizontal tray next above.

10. A multiple utility rack as claimed in claim 9 wherein in each of said horizontal utility trays comprises: a rectangle of wire having two relatively longer sides and two shorter ends; a pair of downwardly extending crimps formed in each of the ends of said rectangle, one of said crimps being disposed adjacent to each of the corners of said rectangle; a plurality of downwardly extending flat-bottom U-shaped wires secured transversely of said rectangle, said wires being disposed in parallel relationship to each other and the ends of said rectangle; one or more longitudinal wire braces secured to the underside of said flat-bottomed U-shaped wires, said braces being disposed in parallel relationship to the sides of said rectangle; and suspension means movably secured to the ends of said rectangle, each of said suspension means being secured to one of said ends of said rectangle adjacent to one of said crimps but disposed outwardly thereof.

11. A multiple utility rack as claimed in claim 10 wherein each of said suspensions means comprises a length of wire having a closed loop at one end for movably securing said length of wire to an end of said rectangle, said closed loop being disposed outwardly adjacent to one of said crimps, and an open hook-shaped bend at the other end for connecting each of said suspension means into the corresponding downwardly extending crimp of the rack or tray structure next above.
